DISCHARGER

Richard C. Coupland, United States Army,
Norfolk, Va.

Application October 5, 1932, Serial No. 636,365

4 Claims. (Cl. 42—1)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a discharger especially adapted for attachment to a rifle and capable of firing a grenade or pyrotechnic signal.

The main object of the invention is to provide a discharger in which a barrel has a long recoil stroke in a stationary receiver that is adapted to contain an auxiliary recoil check.

10 A further object is to provide a novel firing pin and trigger mechanism that may be conveniently associated with the receiver and barrel.

15 To these and other ends, the invention consists in the construction, arrangement and combination of elements described hereinafter and pointed out in the claims forming a part of this specification.

20 A practical embodiment of the invention is illustrated in the accompanying drawing, wherein: Fig. 1 is a view in side elevation of the improved discharger.

Fig. 2 is a vertical sectional view taken generally on the line 2—2 of Fig. 5.

Fig. 3 is a plan view, parts being shown in section.

Fig. 4 is a longitudinal sectional view of the firing pin, and

30 Fig. 5 is a view in rear elevation of the discharger.

Referring to the drawing by character of reference:

The discharger consists generally of a barrel 35 A movably mounted in a receiver B that is secured to the muzzle of a rifle C in a manner similar to a bayonet.

40 The receiver comprises a cylindrical body 5 whose upper surface includes a socket 6 for receiving the muzzle of the rifle barrel and whose base 7 is formed with a groove 8 for receiving the lug 9 provided on the rifle for attachment of a bayonet. A bushing 10 (Fig. 4) mounted in the base 7 of the body 5 has an externally threaded portion 11 projecting rearwardly from the base to carry a nut 12. The nut is circular with a segment cut away to provide a flat side 13. When mounting the discharger on the rifle by a movement parallel to the axis thereof in order to connect the lug 9 and groove 8, the flat side 13 of the nut is disposed parallel to and clear of the floor 14 of the groove 8. Partial rotation of the nut disposes it in rear of the lug 9 where it serves to prevent withdrawal of the discharger. The nut

is held in position of adjustment by means of a click latch 15.

A pair of spaced tubes 16—16 secured to the upper surface of the body 5 each receives one of a pair of tubes 17—17 secured to the forward end of the barrel A. Within each set of telescoping tubes is a spring 18 confined between the rear end 19 of the tube 16 and a diaphragm 20 in the tube 17. A rod 21 secured to the end 19 has a head 22 disposed in front of the diaphragm and engageable thereby whereby to limit forward movement of the tube 17 under the influence of the spring 18.

10 As shown in the drawing the tubes 17 are preferably secured to a collar 23 on the front end of the barrel A. An aperture 24 extending through the barrel and the collar enables a portion of the gases of discharge to strike a baffle plate 25 secured to the under side of the collar. Such action results in checking recoil of the barrel and arresting climb of the rifle as is well understood in the art.

20 Referring to Fig. 2 the base 26 of the barrel is provided centrally with an aperture 27 for receiving a tube 28 threadedly mounted on a forwardly projecting portion 29 of the bushing 10. When thus assembled the tube is held against forward displacement by the engagement of the bushing with one side of the base 7 of the receiver and it is held against rearward displacement by 30 means of a collar 30 engageable with the other side of the base.

25 A liner 31 in the front end of the tube 28 carries an apertured plug 32 that serves to limit forward movement of a firing-pin head 33. A spring 34 embracing the stem 35 of the firing pin is confined between the portion 29 of the bushing 10 and the rear face of the liner 31. The ends of the spring are also available for contact with the rear face of the firing-pin head and with a pair of 40 lugs 36—36 on the stem 35. The lugs 36 are normally disposed within the front end of the portion 29 of the bushing 10 and engage in grooves 37—37 therein. The lugs and the rear ends of the grooves cooperate to limit retraction 45 of the firing pin.

35 The rear portion 35a of the stem 35 extends through the bushing 10 and is squared therein to prevent rotation of the firing pin. The extremity of the squared portion 35a carries a cocking 50 arm 38 which is preferably in the form of half of a cup so that the nut 12 may be disposed therein when the firing pin is in forward position.

45 A trigger 39 slidably mounted in a passage 40 55

in the base of the receiver in a position parallel to the firing pin is formed with a slot 41 in which a latch 42 is pivotally mounted on a pin 43. The rear end 44 of the latch is engageable with the 5 cocking arm 38 and is normally maintained in this position by means of a spring 45 acting on the forward end 46 of the latch and holding said forward end against the wall of the passage 40.

A cam 47 secured to the base 7 at the rear end 10 of the passage 40 is provided for tripping the latch and also for limiting the rearward stroke of the trigger.

As clearly shown in Fig. 3 the cocking arm 38 is also engageable with the click latch 15 and 15 serves as a means for moving the click latch out of contact with the nut 12.

A series of resilient rings 48 may be placed in the receiver in rear of the barrel to supplement the springs in checking recoil of the barrel.

20 The projectile to be fired from the device consists of a grenade or pyrotechnic signal carrying its own propelling charge and adapted to be inserted in the barrel through the muzzle.

25 In the normal position the firing pin and trigger 38 are as shown in Figs. 3 and 4, the point of the firing-pin head 33 being withdrawn inside the plug 32 so that a projectile may be safely inserted in the barrel, and the latch 42 of the trigger being extended so as to be engageable 30 with the cocking arm 38.

35 When the trigger is retracted, the latch, by virtue of its engagement with the cocking arm, will also retract the firing pin. During this movement the firing pin head 33 picks up the spring 34 and compresses it. When the latch is tripped on striking the cam 47 the firing pin is released and is driven forward by the compressed spring. The spring is arrested by the rear face of the liner 31 but the inertia of the 40 pin carries it forward through the apertured plug where it strikes the primer of the projectile. During this additional forward movement of the firing pin the lugs 36 thereon act on the rear end of the spring to compress it and provide the energy for ultimately restoring the pin to its 45 normal position.

When the projectile is fired from the barrel,

the reaction of the propellant force causes the barrel to move rearwardly in recoil compressing the springs 18 and the resilient rings 48 and storing up the energy required to return it into battery.

5 Troops not equipped with a rifle will use an appropriate substitute as a support.

I claim:

1. A discharger including a cylindrical receiver, a barrel mounted for sliding movement in the receiver, a recoil and counterrecoil mechanism associated externally with the receiver and barrel, resilient rings within the receiver between its base and the base of the barrel, a tube secured to the base of the receiver and extending 15 through the base of the barrel, and a firing pin within the tube.

2. A discharger including a cylindrical receiver, a barrel mounted for sliding movement in the receiver, resilient rings within the receiver between its base and the base of the barrel, a tube secured to the base of the receiver and extending 20 through the base of the barrel, and a firing pin within the tube.

3. A discharger including a cylindrical receiver, a barrel mounted for recoil movement in the receiver, a tube secured to the base of the receiver in rear of the barrel and extending 25 through the base of the barrel, a firing pin within the tube, and means for checking recoil of the barrel and restoring it to battery.

4. In a firing mechanism, a fixed tube having internal shoulders provided adjacent its ends and having a non-circular bearing in its rear end formed with grooves, a spring confined 35 between the shoulders, a firing pin within the spring and having a non-circular stem extending through the bearing, a head on the front end of the firing pin, lugs on the stem of the firing pin engaging in the grooves of the bearing, the head 40 and lugs engageable with respective ends of the spring, an arm on the rear extremity of the firing pin, a trigger mounted for movement parallel to the firing pin, and means on the trigger for releasably engaging the arm of the firing pin. 45

RICHARD C. COUPLAND.
